ATTORNEY

UNITED STATES PATENT OFFICE.

FERDINAND FRANCIS BRUCKER, OF AKRON, OHIO, ASSIGNOR TO THE MILLER RUBBER COMPANY, A CORPORATION OF OHIO.

TIRE-BUILDING APPARATUS.

Application filed September 5, 1913. Serial No. 788,306.

To all whom it may concern:

Be it known that I, FERDINAND F. BRUCKER, citizen of the United States, residing at Akron, Ohio, have invented certain new and useful Improvements in Tire-Building Apparatus, of which the following is a specification.

My present invention relates to improvements in apparatus for causing frictioned fabric such as employed in forming or building pneumatic vehicle tires to be smoothly and effectively applied to the rotary cores or circular mandrels, and the invention has among others for its objects to provide a simple, durable and efficient form of apparatus, capable of being easily controlled by a single operator to secure the application of the fabric in a smooth and effective manner.

20 The invention includes the novel features of construction and arrangement and combination of parts hereinafter described and particularly defined by the appended claims.

A form of apparatus constructed in accordance with my invention is illustrated in the accompanying drawings, in which

Figure 1 is a plan view;

Figure 2 is a side elevation;

Figure 3 is a front elevation;

30 Figure 4 is part of Figure 1; and

Figure 5 is a section of Figure 4 on line 4-4.

The apparatus above indicated is intended to press or draw the fabric down smoothly and firmly around the ring core or mandrel after it has been applied thereto or wound thereon in the form of a strip or strips in any suitable manner.

In Figure 1 a portion of the mandrel is indicated conventionally at 1, and the fabric in the position it assumes on being wound thereon and before being pressed or spun down around the core, at 2.

45 The pressing or spinning down of the fabric is accomplished by a pair of wheels or discs 3 which are mounted for free rotation on a pair of arms 4 which have their shanks 4^a slidably mounted in brackets 5 swiveled on the ends of arms 6.

50 Springs 7 encircling the shanks 4^a and bearing against collars or flanges 8 thereon permit a yielding action of the shank;

4^a and consequently the discs 3 when passed by splices in the fabric 2.

The arms 6 are mounted upon a slidable carriage 9 supported by the frame 10 of the machine, so that they may be moved toward and from the core; and in order that they may be simultaneously separated sufficiently to act at the proper points on the core and 60 pressed thereagainst to effect the shaping or spinning action I mount them rigidly upon hollow shafts 11 journaled in the frame of the carriage and carrying intermeshing gears 11^a which cause them to be rotated in 65 unison. One of these shafts carries at its lower end, a bevel gear 12 which meshes with a vertically disposed bevel gear 13 slidably keyed to a shaft 14 to which is affixed an arm 15. This, in turn, is connected by a 70 link 16 with arm 17 of shaft 18 to which is connected treadle lever 19. This treadle lever 19 is normally held elevated by springs 20, and when in this position holds the arms 6 separated. By this construction arms 6 may 75 be moved independent of the rotating motion of arms 4 as I will further explain in a later paragraph of this description.

When the carriage has moved forward until the discs are in proximity to the core, 80 the operator places his foot on the treadle and depresses it until the discs are pressed towards each other, causing them to impinge against the fabric on the core at the proper distance on each side of the center thereof, 85 and governs the pressure of the discs on the fabric by the amount of pressure of his foot.

Power is imparted to move the carriage forward by a wheel 21 which may be driven from any convenient source of power, which wheel is fast on a shaft 22 carrying a helical gear 22^a which meshes with a helical gear 23 on screw shaft 24 extending longitudinally of the machine. The carriage is provided at a suitable point with two half nuts 49 operated by hand lever 26 so that when the half nuts and screw are brought into engagement, the carriage will be fed forward.

100 The half nuts 49 are each provided with a pin 48 which extends upwardly through lateral guiding slots in carriage 9 and scroll slots 53 in a circular cam 47. Cam 47 is

sunk in a recess in carriage 9 and rigidly fastened to stud 46 which carries hand lever 26 at its upper extremity. In the position shown in Figures 4 and 5 the half nuts 49 are disengaged from the feed screw 24. A quarter revolution in a clockwise direction of hand lever 26 and cam 47 causes the half nuts 49 to engage with screw 24 by reason of the pins 48, carried by half nuts 49 being forced together by the scroll slots 53 in cam 47.

Stud 46 is surrounded by a coil spring 50. One end of coil spring 50 is rigidly connected to cam 47. The other end is rigidly connected to barrel 51 which surrounds coil spring 50 and supports stud 46. Coil spring 50 resists motion of cam 47 in a clockwise direction and is of sufficient strength to disengage half nuts 49 from feed screw 24.

20 Cam 47 is provided with a notch 52 in its periphery and a latch 44 slidably mounted in a recess in carriage 9 and pressing radially against cam 47 is so placed as to enter notch 52 in cam 47 when half nuts 49 are engaged with the feed screw 24, said pressure being produced by a spring 45. Latch 44 locks half nuts 49 in engagement with feed screw 24 holding them in said engagement until it is radially withdrawn.

30 Latch 44 is provided with an upwardly projecting pin 56 which is engaged by a slotted hole in a lever 42. Lever 42 is pivotally connected at its center to carriage 9 by a screw 43 and has a bent end 55. Frame 35 10 is provided with a longitudinal T slot 56* and a movable stop 41 is clamped to frame 10 by means of this slot and a bolt and nut 57. Stop 41 is provided with an inclined vertical surface of such shape as to 40 cause lever 42 to withdraw latch 44 from cam 47 when the carriage has moved far enough for lever 42 to impinge against stop 41. Stop 41 may be locked in such a position that when discs 3 have just accomplished the applying of the fabric the half nuts 49 will be disengaged.

When the half nuts 49 are disengaged from the screw, the carriage is automatically retracted by a cable 27 which is acted upon 50 by a weight 28, one end of the cable being fast to a bracket 29 and thence passing around pulley 30 on the weight and over pulley 31 on the machine frame to the carriage, to which it is secured as indicated 55 at 32.

It is necessary in order to secure the best results, that the angle of the discs 3 should be changed as they progress around the core, so as to maintain them at about the same 60 angle or tangent to the periphery of the core, or to cause them to act on the fabric always at the most efficient angle. It is also a great advantage to be able to maintain this angle when stitching or spinning the

fabric around the beads of the different slopes of tires.

To accomplish this I connect the rear ends of the arms 4 by links 33, preferably adjustable by turnbuckles, with pivot pins 34 carried by discs 35—35' which have intermeshing toothed edges, so that they are caused to rotate in unison.

One of these discs 35 is fast on shaft 36 rotatably supported in the hollow shaft 11, and shaft 36 carries at its lower end a bevel gear 37 which meshes with a bevel gear 38 on a shaft journaled in bearing bracket 39 and carrying hand wheel 40. The other disc 35' is free to revolve on shaft 36' and is driven by disc 35.

By rotating hand wheel 40 the angle of the discs may be changed independent of the movement of arms 6 to suit the operator and as the shaping of the fabric progresses.

It will be observed that instead of moving 85 the carriage supporting the fabric shaping or forming rollers towards the core, the latter might be moved towards and from the support for the fabric shaping devices, but the former is preferable and hence is the 90 construction which I particularly describe.

It will be understood that I do not limit myself to the precise details of construction herein shown and described, as various modifications thereof might be made without departing from the spirit of my invention.

Having thus described my invention what I claim is:

1. Apparatus for shaping tire fabric upon a core, comprising a carriage, means for moving the same toward and from the core, a pair of arms pivotally mounted upon the carriage, with means for moving them towards and from each other, supplemental arms pivotally mounted upon said first named arms, fabric shaping devices carried by said supplemental arms, and means for swinging said supplemental arms toward and from each other upon their pivots.

2. In combination a revoluble core, a support for a fabric shaping device, one of said elements being movable towards and from the other, a pair of fabric shaping devices for cooperating with the core, a pair of arms pivotally mounted upon said support, means for swinging said arms in unison towards and from each other, a pair of supplemental arms pivotally supported upon said first named arms and supporting the fabric shaping devices, and means for swinging said supplemental arms upon their pivots to vary the inclination of the shaping devices.

3. In combination a revoluble core, a support for fabric shaping devices, one of said elements being movable towards and from the other, a pair of arms pivotally carried by said support, positively operated means for swinging them towards and from each

other, brackets pivotally carried by said arms, supplemental arms slidably carried by said brackets, springs exerting tension on said supplemental arms, forming discs or 5 rollers journaled upon said supplemental arms, and positively operated means for swinging said supplemental arms.

4. In combination a carriage, a slow speed mechanism for moving said carriage in one 10 direction, means for automatically releasing said carriage therefrom, quick return mechanism for moving said carriage in the opposite direction, a pair of fabric shaping devices, pivotal supports for said fabric shaping devices supported on the carriage and movable towards and from each other; and means for varying the angular position of 15 said fabric shaping devices.

5. In combination a main frame, a carriage, a power driven screw carried by said main frame, means for connecting and means for automatically disconnecting said carriage from said power driven screw, a tension device connected to said carriage for 20 moving it in a direction opposing to that in which it is moved by the screw, and fabric shaping devices supported from said carriage.

6. In combination a ring core and a support 30 for fabric shaping devices, one of said elements being movable towards and from the other, a pair of arms pivotally mounted upon said support, treadle actuated means for moving said arms towards and from 35 each other, a pair of supplemental arms pivotally supported from said first named arms and carrying devices for shaping the fabric on the core, and hand actuated means for swinging said supplemental arms on their 40 pivots.

7. In combination a carriage, a pair of shafts geared to rotate in unison and supported by said carriage, manually actuated means for imparting movement to one of 45 said shafts, a pair of arms rigidly fixed to said shafts, supplemental arms pivotally supported from said first named arms, forming discs or rollers carried by said supplemental arms, a second pair of shafts on said 50 carriage, a pair of discs geared to rotate in unison keyed thereon, a pair of links connected respectively at one end to said supplemental arms and at the other end eccentrically connected to said discs, and manually actuated means for rotating said discs 55 independently of the manually actuating means for said first mentioned shafts, substantially as described.

8. The combination of a support, a rotatable tire-form, a carriage movable in relation to the form, a fabric-pressing member carried by and rotatable on a vertical axis on the carriage, actuating mechanism for bodily shifting said vertical axis of the pressing-

member on the carriage during the rotation 65 of the form, actuating mechanism for moving said carriage in relation to the form during its rotative movement, and means for automatically arresting the actuation of said carriage-actuating mechanism when the 70 carriage reaches a predetermined position.

9. The combination of a support, a rotatable tire-form, a carriage moving in relation to the form, a fabric-pressing member carried by and rotatable on a vertical axis on the carriage, actuating mechanism for bodily shifting said pressing-member on the carriage during the rotation of the form, actuating mechanism for moving said carriage in relation to the form during its rotative 80 movement, means for automatically arresting the actuation of said carriage-actuating mechanism when the carriage reaches a predetermined position, and means for moving said pressing-member in relation to the form 85 independently of but during the movement of the carriage.

10. In a tire-making machine, a support, a carriage thereon, means for effecting movement of said carriage on the support in 90 a plurality of directions including a carriage-feeding mechanism, a control-lever therefor, a stop device engageable with the control-lever to actuate the same automatically to arrest movement of the carriage and 95 release the same from the carriage feeding mechanism, and power operated means for returning the carriage to starting position after being released from the carriage feeding mechanism by the stop device. 100

11. A tire-making machine including a support, a tire form juxtaposed thereto, a carriage movable in relation to the form, means for effecting an advancing movement of the carriage toward the form, means for 105 automatically effecting a receding movement of the carriage away from the form, and a fabric-manipulating device movable with the carriage and adapted to be also actuated independently thereof. 110

12. In a tire building machine, the combination with a rotatable core adapted to receive a strip of fabric; of a spinner, means for automatically moving said spinner toward the axis of rotation of the core; and a 115 manually operated device constituting the whole means for pressing said spinner into contact with the fabric on the core.

13. The combination with a shaping core; of a spinner, means for automatically moving said spinner towards the axis of the core; a manually operated device adapted to press said spinner into contact with the fabric on the core; and a yielding connection between said spinner and said manually operated device. 120 125

14. In a tire building machine, the combination with a rotatable core adapted to re-

ceive a strip of fabric, of a spinner; means for automatically moving said spinner towards the axis of rotation of the core; means for yieldingly holding said spinner away from the core; and a manually operated device for pressing said spinner into contact with the fabric on the core.

15. In combination in a tire making machine, a rotary tire-form, fabric-pressing members to act on opposite sides of the tire-form, a support for the said members, said tire-form and support having relative movement to make the fabric-pressing members traverse the form substantially radially thereof, means for applying pressure to the fabric-pressing members to force them towards the central plane of the form during their traversing movement, and means for causing automatic retraction of the fabric-pressing members laterally from the form and from each other when the said pressure is relieved, substantially as described.

16. In combination in a tire making machine, a rotary tire-form, fabric-pressing members to act on opposite sides of the tire-form, a support for the said members, said tire-form and support having relative movement to make the fabric-pressing members traverse the form substantially radially thereof, means for applying pressure to the fabric-pressing members to force them towards the central plane of the form during their traversing movement, and means for causing automatic retraction of the fabric-pressing members laterally from the form and from each other when the said pressure is relieved, substantially as described.

17. In combination in a tire making machine, a rotary tire-form, fabric-pressing members to act on opposite sides of the tire-form, a support for the said members, said tire-form and support having relative movement to make the fabric-pressing members traverse the form substantially radially thereof, means for applying pressure to the fabric-pressing members to force them towards the central plane of the form during their traversing movement, and means for causing automatic retraction of the fabric-pressing members laterally from the form and from each other when the said pressure is relieved, said pressure acting in opposition to the force of the automatic retracting means.

18. In combination in a tire making machine, a rotary tire-form, fabric-pressing members to act on opposite sides of the tire-form, a support for the said members, said tire-form and support having relative movement to make the fabric-pressing members traverse the form substantially radially

thereof, means for applying pressure to the fabric-pressing members to force them towards the central plane of the form during their traversing movement, and means for causing automatic retraction of the fabric-pressing members laterally from the form and from each other when the said pressure is relieved, said pressure applying means being common to both fabric-pressing means, substantially as described.

19. In combination in a tire making machine, a rotary tire-form, fabric-pressing members to act on opposite sides of the tire-form, a support for the said members, said tire-form and support having relative movement to make the fabric-pressing members traverse the form substantially radially thereof, means for applying pressure to the fabric-pressing members to force them towards the central plane of the form during their traversing movement, and means for causing automatic retraction of the fabric-pressing members laterally from the form and from each other when the said pressure is relieved, said fabric-pressing members being individually yieldable to accommodate themselves to irregularities in the work, substantially as described.

20. In combination in a tire making machine, a rotary tire-form, fabric-pressing members to act on opposite sides of the tire-form, a support for the said members, said tire-form and support having relative movement to make the fabric-pressing members traverse the form substantially radially thereof, means for applying pressure to the fabric-pressing members to force them towards the central plane of the form during their traversing movement, and means for causing automatic retraction of the fabric-pressing members laterally from the form and from each other when the said pressure is relieved, each of said pressing members being pivotally mounted to change their angular position in relation to the form, and means for turning said members, substantially as described.

21. In combination in a tire making machine, a rotary tire-form, a support, one of said parts being movable relative to the other, and fabric-pressing members having the following characteristics, pivotally mounted on the support for changing their angular relation to the tire-form; movable towards the central plane of the tire-form under a follow up pressure as they are traversing said form radially thereof; individually yieldable to compensate for irregularities in the work and automatically retracted laterally from the sides of the form upon cessation of said follow up pressure, substantially as described.

22. In combination in a tire making machine, a rotary tire-form, fabric-pressing members to act on opposite sides of the tire-

- form, a support for the said members, said tire-form and support having relative movement to make the fabric-pressing members traverse the form substantially radially thereof, means for applying pressure to the fabric-pressing members to force them towards the central plane of the form during their traversing movement, and spring means stressed when the fabric-pressing members are forced against the form for causing automatic retraction of the said members laterally from the sides of the form after said pressure is relieved, substantially as described.
- 15 23. In combination in a tire making machine, a rotatable tire-form, a support, one of said parts being movable towards and from the other, fabric-pressing means for traversing the sides of the tire-form, means for forcing the fabric-pressing members against the material on the tire-form, means for changing the angular position of the fabric-pressing members in relation to the work on the form, and means for automatically moving the fabric-pressing members laterally away from the sides of the form when the action of the said forcing means ceases, substantially as described.
- 20 24. In combination in a tire making machine, a rotatable tire-form, a support, one of said parts being movable towards and from the other, fabric-pressing means for traversing the sides of the tire-form as a result of the movement of the said movable part, means for forcing the fabric-pressing members against the material on the tire-form, means for changing the angular position of the fabric-pressing members in relation to the work on the form, means for arresting the movable part at a predetermined point, and means for automatically moving the fabric-pressing members laterally away from the sides of the form when the action of the said forcing means ceases, substantially as described.
- 25 25. In combination in a tire making machine, a rotary tire-form, a support, one of said parts being movable relative to the other, and fabric-pressing members to operate on opposite sides of the form having the following characteristics, shiftably mounted on the support with means for changing their angular relation to the work on the tire-form, movable against the work on the tire-form under follow up pressure as they traverse said form radially thereof, individually yieldable to compensate for irregularities in the work, and automatically and simultaneously retracted laterally from the sides of the form upon cessation of said follow up pressure, substantially as described.
- 30 26. In combination in a tire making machine, a rotary tire-form, a support, one of said parts being movable relative to the other, and fabric-pressing members to operate on opposite sides of the form having the following characteristics, shiftably mounted on the support with means for changing their angular relation to the work on the tire-form, movable against the work on the tire-form under follow up pressure as they traverse said form radially thereof, individually yieldable to compensate for irregularities in the work, and automatically and simultaneously retracted laterally from the sides of the form upon cessation of said follow up pressure, substantially as described.
- 35 27. In combination, a tire form, a support, one of which has movement towards and from the other, fabric-pressing members on the support which are caused by said relative movement to traverse the material on the form in a direction substantially radial to the form, said members having movement laterally of the form to press the material thereagainst, means for exerting pressure to effect said lateral movement, said members having automatic separating movement from each other and laterally from the sides of the form when said pressure ceases, and independent of the relative traversing movement of the form and support, substantially as described.
- 40 28. In combination in a tire-making machine, a rotary tire-form, fabric-pressing members to act on opposite sides of the tire-form, a support for the said members, said tire-form and support having relative movement to make the fabric-pressing members traverse the form substantially radially thereof, means for applying pressure to the fabric-pressing members from a source of power common to them both to force them towards the central plane of the form uniformly during their traversing movement, said fabric-pressing members being supported on vertical pivots about whose axes they turn, and means for turning said members uniformly and simultaneously to change their angular positions in relation to the form, substantially as described.
- 45 29. In combination in a tire making machine, a rotary tire-form, fabric-pressing members to act on opposite sides of the tire form, a support for the said members, said tire-form and support having relative movement to make the fabric pressing members traverse the form substantially radially thereof, means for applying pressure to the fabric pressing members from a source of power common to them both to force them towards the central plane of the form uniformly during their traversing movement, said fabric pressing members being each individually yielding in relation to the work and in opposition to the common force without affecting the pressure exerted by the other upon the form.
- 50 30. In combination in a tire making machine a rotary tire-form, fabric pressing

members to act on opposite sides of the tire form, a support for said members, said tire form and support having relative movement to make the fabric pressing members 5 traverse the form substantially radially thereof, means common to both fabric pressing members to force them against the fabric on the form, substantially uniformly during the traverse of said fabric pressing members 10 along the sides of the form, each of said fabric-pressing members being yieldable against said common pressure without affecting the other, and means for simultaneously and substantially uniformly changing 15 the angular position of the fabric pressing members in relation to the form, substantially as described.

31. In combination in a tire making machine a rotary tire-form, fabric pressing 20 members to act on opposite sides of the tire form, a support for said members, said tire form and support having relative movement to make the fabric pressing members traverse the form substantially radially 25 thereof, means common to both fabric pressing members to force them against the fabric on the form substantially uniformly during the traverse of said fabric pressing members along the sides of the form, and 30 means for simultaneously and substantially uniformly changing the angular position of the fabric pressing members in relation to the form, substantially as described.

32. In combination in a tire making machine, a rotatable tire-form, carrier means, with means for moving one of said parts in 35 relation to the other, fabric-pressing members, one for each side of the tire form, a supporting member for each fabric pressing 40 member in which the shank thereof is slid- able, a pivot post for each supporting mem- ber mounted in the carrier means, and means for turning the support about the pivot 45 axis for changing the angular relation of the fabric pressing members in respect to the tire form, each of said fabric pressing members being spring pressed to be auto- matically and individually yieldable in re- 50 spect to the tire form to compensate for ir- regularities in the work.

33. In combination a rotatable tire form, supporting means, means for giving move- 55 ment to one of said parts towards the other, rotary fabric pressing members, one for each side of the tire form, supporting brackets for said pressing members in respect to which each pressing member has sliding movement towards and from the central plane of the tire form and in a direction 60 substantially perpendicular to the axis of the rotary pressing members, each bracket hav- ing a pivot mounted in the supporting means about the axis of which the bracket turns, and means common to both brackets 65 for turning them uniformly, to change the

angular relation of the pressing members to the center plane of the tire form, sub- stantially as described.

34. In combination, a rotary tire-form, a support, one of said parts being movable 70 towards and from the other, fabric-pressing members on the support, one for each side of the form to traverse the same substantially radially of the form, means for causing the holding of the fabric-pressing members nor- mally retracted laterally from the sides of 75 the form, and means for imposing a follow- up pressure to the fabric-pressing members for advancing them simultaneously against the form and in opposition to said holding 80 means during their traversing movement radially thereof, said advancing pressure means being common to both fabric-pressing devices.

35. In combination in a tire building ma- 85 chine, a tire-form, a fabric-pressing mem- ber, means for giving movement to one of said parts relative to the other for position- ing the pressing member to engage the form, supports for the fabric pressing members 90 movable towards and from the central plane of the tire form, said fabric-pressing mem- bers being turnable about vertical support- ing pivots on said movable supports in rear 95 of their working faces, means for forcing the fabric-pressing means against the tire- form, and means for turning the fabric- press- ing members about their pivots while maintaining contact with the form to change their angular relation to the form. 100

36. In combination in a tire building ma- chine, a tire-form, fabric-pressing members, a carriage on which the fabric-pressing members are mounted, means for forcing the pressing members against the form, means for advancing the carriage in a di- 105 rection substantially radially of the form, and means for automatically releasing the carriage from the advancing means for the return of the carriage independent of the 110 advancing means.

37. In combination in a tire building ma- chine, a rotary tire-form, a support, means for moving one of said parts relative to the other fabric-pressing members movably 115 mounted on the support, one for each side of the tire-form, to traverse the sides of the form, as a result of the relative move- ment of the said parts, means for auto- matically arresting the movable part at a 120 predetermined point in the traverse of said members, and means for forcing the fabric- pressing members against the sides of the form and for automatically retracting them away laterally from the sides of the form 125 when the action of said fabric-pressing means upon the form ceases, substantially as described.

38. In combination in a tire building ma- chine, a rotary tire-form, a support, means 130

- for moving one of said parts relative to the other fabric-pressing members movably mounted on the support, one for each side of the tire-form to traverse the sides of the form, as a result of the relative movement of the said parts, means for turning the fabric-pressing members to different angular relations to the sides of the form, means for forcing the said fabric-pressing members 5 against the sides of the form and for automatically retracting them laterally away from the sides of the form, and means for automatically releasing the moving part from its driving means for the separation 10 of the tire-form and support to normal position, substantially as described.
39. In combination, a rotary tire-form, a frame, a carrier to reciprocate on said frame towards and from the tire-form, fabric-pressing members movably mounted on the carrier, means for forcing said fabric-pressing members against the form, a rotary screw shaft for advancing the carrier, and means for automatically releasing the carrier, and 15 from the screw shaft at a predetermined point in the advancing movement of said carrier for the return of said carrier to normal position independent of the said screw shaft.
40. In combination, a rotary tire-form, a frame, a carrier to reciprocate on said frame towards and from the tire-form, fabric-pressing members movably mounted on the carrier, means for forcing said fabric-pressing members against the form, a rotary screw shaft for advancing the carrier, and means for automatically releasing the carrier from the screw shaft at a predetermined 20 point in the advancing movement of said carrier for the return of said carrier to normal position independent of the said screw shaft, said releasing means including a nut with connections for operating said nut and a contact device on the frame for operating 25 said connection, substantially as described.
41. In combination, a rotary tire-form, a frame, a carrier to reciprocate on said frame towards and from the tire-form, fabric-pressing members movably mounted on the carrier, means for forcing said fabric-pressing members against the form, a rotary screw shaft for advancing the carrier to make the fabric-pressing members traverse the sides of the tire-form, means for automatically disconnecting the carrier from the screw shaft at a predetermined point in the advancing movement of the carrier, and a hand lever for again connecting the carrier and screw shaft, substantially as described. 30
42. In combination, a rotary tire-form, a frame, a carrier to reciprocate on said frame towards and from the tire-form, fabric-pressing members movably mounted on the carrier, means for forcing said fabric-pressing members against the form, a rotary 35

screw shaft for advancing the carrier, a nut on the carrier for engaging the screw shaft, a stop on the frame, means on the carrier operated by contact with the stop for withdrawing the nut from the screw shaft, and a handle connected with said means for restoring the nut into engagement with the screw shaft, substantially as described. 40

43. In combination, a rotary tire-form, a frame, a carrier slidable on the frame, fabric-pressing means movably mounted on the carrier, machine driven means for advancing the carrier, connections operated by the foot of the operative for forcing the fabric-pressing means against the tire-form, 45 said fabric-pressing means being mounted for assuming different angular positions in respect to the plane of the tire-form, and hand operated means for changing the angularity of the said fabric-pressing members, and means for automatically arresting the carrier at a predetermined point. 50

44. In combination, a rotary tire-form, a frame, a carrier slidable on the frame, fabric-pressing means movably mounted on the carrier, machine driven means for advancing the carrier, connections operated by the foot of the operative for forcing the fabric-pressing means against the tire-form, 55 said fabric-pressing means being mounted for assuming different angular positions in respect to the plane of the tire-form, and hand operated means for changing the angularity of the said fabric-pressing members, and means for automatically arresting 60 the carrier at a predetermined point, said foot power connections being mounted on the main frame, and maintaining connection with the fabric-pressing means in all positions of the sliding carrier on the frame, and 65 said hand operated connections being mounted on the carrier, substantially as described. 70

45. In combination in a tire making machine, a rotary tire-form, a frame, a carrier slidable on the frame, a rotary screw shaft supported in the frame for advancing the carrier, fabric-pressing members, one for each side of the form, a rock shaft arranged parallel with the screw shaft and mounted in the frame, means on the carrier slidably connected with the rock shaft to be operated thereby in all positions of the carrier for forcing the fabric-pressing members against the form, and manually operable means for turning the rock shaft. 75

46. In combination in a tire making machine, a rotary tire-form, a frame, a carrier slidable on the frame, a rotary screw shaft supported in the frame for advancing the carrier, fabric-pressing members, one for each side of the form, a rock shaft arranged parallel with the screw shaft and mounted in the frame, means on the carrier slidably connected with the rock shaft to be operated thereby in all positions of the carrier for 80

forcing the fabric-pressing members against the form, and a foot treadle for turning the rock shaft, and hand operated means on the carrier for changing the angularity of the 5 fabric-pressing members in respect to the tire-form.

47. In combination in a tire making machine, a rotary tire-form, a frame, a carrier 10 slideable on the frame, a rotary screw shaft supported in the frame for advancing the carrier, fabric-pressing members, one for each side of the form, a rock shaft arranged parallel with the screw shaft and mounted in the frame, means on the carrier slidably 15 connected with the rock shaft to be operated thereby in all positions of the carrier for forcing the fabric-pressing members against the form, and manually operable means for turning the rock shaft, and means for automatically disconnecting the carrier from the 20 screw shaft at a predetermined point in the advance movement of the carrier.

48. In combination in a tire making machine, a tire-form, a support, means for giving motion to one of said parts towards the other, fabric-pressing members movably mounted on the support and traversing the opposite sides of the form, a treadle with connections for moving the fabric-pressing 25 members towards each other and against the sides of the form, and means for causing retraction of the fabric-pressing members away from the form when pressure on the treadle is relieved, substantially as described.

49. In combination in a tire making machine, a tire-form, a support, means for giving motion to one of said parts towards the other, fabric-pressing members movably mounted on the support and traversing the 30 opposite sides of the form, a manually operable device with connections for moving the fabric-pressing members towards each other and against the sides of the form, and means for causing retraction of the fabric-pressing members away from the form when 35 pressure on the manually operable device is relieved, substantially as described.

50. In combination, a tire-form, a support, 40 fabric-pressing members on the support, means for moving one of said parts, in relation to the other to make the fabric-pressing members traverse the sides of the form, rotatable means connected with the fabric-pressing means for moving them to or from the tire-form, said fabric-pressing 45 members being turnably mounted to assume different angular positions relative to the form, rotatable means arranged coaxially with the rotatable means first mentioned with connections to the fabric-pressing members for changing their angularity, and means for operating said rotatable members.

51. In combination, fabric-pressing members, a pair of hollow shafts geared together, arms on said shafts carrying the fabric-press-

ing means pivotally, a second pair of shafts extending through the hollow shafts and geared together at their upper ends, connections between the latter gears and the fabric-pressing members for turning them to 70 change their angularity, and means for operating the shafts, substantially as described.

52. In combination, fabric-pressing members, a pair of hollow shafts geared together, 75 arms on said shafts carrying the fabric-pressing means pivotally, a second pair of shafts extending through the hollow shafts and geared together at their upper ends, connections between the latter gears and the fabric-pressing members for turning them to 80 change their angularity, a carrier for said shafts, a manually operable device mounted on the carrier for operating the inner shafts, a frame, a rock shaft mounted therein and having a splined driving connection with one 85 of the hollow shafts and a foot lever for operating the rock shaft, substantially as described.

53. In combination, a tire-form, a support, 90 fabric-pressing members mounted on the support movable to be forced against the sides of the form, manually operable means with connections to both of the fabric-pressing members for forcing them against the form simultaneously and substantially uniformly and with a pressure at the will of the operator, and means for retracting the fabric-pressing members away from the sides of the form when pressure on the manually operable device is relieved, substantially as described. 95

54. A tire making machine including a support, power operated means for effecting advancing movement of the support, a fabric-pressing member on and movable with 100 the support, a tire-form juxtaposed to the pressing member, and means to operate the support for thrusting said member towards the form at the will of the operator to initially position the said member, said means 105 thereafter operating to transmit yielding pressure to force the pressing member against the form yieldingly to make it follow the surface configuration of the tire-form, substantially as described. 110

55. In combination in tire making machines, a carriage to have forward and backward movement relative to a tire-form, fabric-pressing members thereon to act on opposite sides of the form, means for pressing 115 the members against the form, said members having automatic separating movement after said pressing action ceases, means for moving the carriage forward, means for automatically arresting the forward movement 120 of the carriage, and manually operating means for determining the time at which the carriage will perform its forward stroke, substantially as described. 125

56. In combination, a tire-form, a support, 130

means for giving movement to one of said parts relative to the other, fabric-pressing means movably mounted on the support and operating along opposite sides of the form, 5 foot power means for moving the fabric-pressing means on the support toward each other, and hand power means for uniformly and simultaneously changing the angular position of the fabric-pressing means relative 10 to each other and to the tire-form, substantially as described.

57. In combination in a tire making machine, a rotary tire-form, a support, one of said parts being movable towards and from 15 the other, fabric-pressing means on the support for traversing the tire-form in a substantially radial direction, and means for transmitting pressure for forcing the fabric-pressing means against the work on the form 20 during said traversing action, said pressure being exerted manually, and the forcing action ceasing as soon as the manual pressure ceases, substantially as described.

58. In combination in a tire making machine, a rotary tire-form, a support, one of said parts being movable towards and from the other, fabric-pressing means on the support for traversing the tire-form, and means for transmitting pressure, exerted manually, 30 to the fabric-pressing means for forcing them against the work on the form, and means for retracting the fabric-pressing means laterally of the form, when the manual pressure is relieved, substantially as described.

59. A tire making machine including a tire-core structure, a fabric-manipulating structure, power-operated means for effecting an advancing movement of one of the 40 structures in relation to the other, and other power-operated means for effecting a receding movement of the advanced structure away from the other.

60. A tire making machine including a tire-core structure, a fabric-manipulating structure, power-operated means for effecting an advancing movement of one of the structures in relation to the other, other power-operated means for effecting a receding movement of the advanced structure away from the other, and fabric-pressing members carried by one of said structures and having an engaging relation with the other, and means for automatically releasing 50 the advanced structure from the first mentioned power-operated means and placing it under the influence of the second at a predetermined point.

61. A tire making machine including a tire-core structure, a fabric-manipulating structure, power-operated means for effecting an advancing movement of one of the structures in relation to the other, a second power-operated means for effecting a receding movement of the advanced structure

away from the other, fabric-pressing members carried by one of said structures and having an engaging relation with the other, and means for actuating said pressing-members.

62. A tire making machine including a tire-core structure, a fabric-manipulating structure, power-operated means for effecting an advancing movement of one of the structures in relation to the other, a second 75 power-operated means for effecting a receding movement of the advanced structure away from the other, fabric-pressing members carried by one of said structures and having an engaging relation with the other, 80 and mechanism for actuating said pressing-members including mechanism for advancing said members in one direction, and means for effecting a receding movement thereof.

63. A tire making machine including a tire-core structure, a fabric-manipulating structure, power-operated means for effecting an advancing movement of one of the structures in relation to the other, a second 85 power-operated means for effecting a receding movement of the advanced structure away from the other, fabric-pressing members carried by one of said structures and having an engaging relation with the other, means for actuating said pressing-members 90 including mechanism for advancing said members in one direction, mechanism for effecting a receding movement thereof, and means for changing the degree of relative angularity of said members during their advancing movement.

64. A tire making machine including a support, a pressing-member positioning-structure thereon, a tire-form structure mounted adjacent the support, power-operated means for changing the relation between said structures whereby advancing and receding movements of one of the structures toward and away from the other are positively effected, and a fabric-pressing instrumentality carried and positionable by the advancing structure in definite relation to the other structure.

65. A tire making machine including a support, a pressing-member positioning-structure thereon, a tire-form structure mounted adjacent the support, power-operated means for changing the relation between said structures whereby advancing and receding movements of one of the structures with respect to the other are positively effected, means for automatically effecting an arresting movement of the advancing structure in predetermined relation to the other, and a fabric-pressing instrumentality 115 carried and positionable by the advancing structure in definite relation to the other structure.

66. A tire making machine including a support, a pressing-member positioning- 120

- structure thereon, a tire-form structure mounted adjacent the support, power-operated means for changing the relation between said structures whereby advancing 5 and receding movements of one of the structures with respect to the other are positively effected, means for automatically disconnecting the moving structure from the power-operating means and thereby effecting an 10 arresting movement of the advancing structure in predetermined relation to the other, and a fabric-pressing instrumentality carried and positionable by the advancing structure in definite relation to the other 15 structure.
67. A tire making machine including a tire-form, a support movable in relation thereto, power-operated means for moving said support, fabric-manipulating devices 20 carried by the support and positionable thereby in relation to the tire-form, means for moving said devices toward the tire-form independent of the positioning movement of the support, power means for returning said devices to normal position, and power-operated means for returning the support to normal position. 25
68. A tire making machine including a support, a carriage thereon, a tire-form juxtaposed to the support, power-operated means for advancing the carriage toward the form, power-operated means for returning it to normal position, and a pressing-member on the carriage normally out of contact with the form and positionable into contacting relation with the form. 30
69. A tire making machine, including a support, a carriage thereon, a tire-form juxtaposed to the support, power-operated 40 means for advancing the carriage toward the form, power-operated means for returning it to normal position, a pressing-member on the carriage normally out of contact with the form and positionable into contacting 45 relation with the form, and means for positioning the member in contacting relation to the form.
70. A tire-making machine including a support, a carriage thereon, a tire-form juxtaposed to the support, power-operated means for advancing the carriage toward the form, power-operated means for returning it to normal position, a pressing-member on the carriage normally out of contact with the form and positionable into contacting 55 relation with the form, and independent means for pressing the member into contact with the form and for changing such contacting relation. 60
71. A tire making machine, including a support, a carriage thereon, a tire-form juxtaposed to the support, power-operated means for advancing the carriage toward the form, power-operated means for returning it to normal position, a pressing-member 65
- on the carriage normally out of contact with the form and positionable into contacting relation with the form, means for pressing the member toward the form, and means for bodily shifting the member while being 70 pressed toward the form. 72. A tire making machine including a tire-form, mechanism for forming tire-material on the form comprising a carriage, power-operated means for advancing the 75 carriage toward the form, power-operated means for effecting a receding movement of the carriage away from the form, and means operating during the movement of the carriage and passing radially across the form 80 for pressing the material thereupon. 73. A tire making machine including a support, a carriage thereon, a rotatable tire-form disposed in juxtaposition to the form, power-operated means for traversing the 85 carriage both toward and away from the form, a pressing-member carried by the carriage and positionable thereby in relation to the form, and means for effecting a positioning movement of said member in relation to the form distinct from the positioning 90 movement of the carriage. 74. A tire-making machine including a support, a carriage thereon, a rotatable tire-form disposed in juxtaposition to the form, power-operated means for traversing the carriage both toward and away from the form, a pressing-member carried by the carriage and positionable thereby in relation to the form, means for effecting a positioning 95 movement of said member in relation to the form distinct from the positioning movement of the carriage and means for effecting motion of said member toward the form distinct from said positioning-movements. 100 75. A tire making machine including a support, a carriage thereon, a rotatable tire-form disposed adjacent the support, means for traversing the carriage toward the form during the rotation thereof, power-operated 105 means for effecting a receding movement of the carriage away from the form, a pressing-device positionable by the carriage in relation to the form, and means for effecting a pressing movement of the device while 110 said carriage is traveling toward the form. 76. A tire making machine including a support, a carriage thereon, a tire-form juxtaposed to the support, power-operated means for advancing the carriage toward 115 the form, means for arresting such advancing movement of the carriage, power-operated means for returning it to normal position, and a pressing-member on the carriage normally out of contact with the form and positionable into contacting relation with the form. 77. A tire making machine including a support, a carriage thereon, a tire-form juxtaposed to the support, power-operated 120 means for advancing the carriage toward the form, means for arresting such advancing movement of the carriage, power-operated means for returning it to normal position, and a pressing-member on the carriage normally out of contact with the form and positionable into contacting relation with the form. 125 78. A tire making machine including a support, a carriage thereon, a tire-form juxtaposed to the support, power-operated 130

means for advancing the carriage toward the form, means for arresting such advancing movement of the carriage, power-operated means for returning it to normal position, a pressing-member on the carriage normally out of contact with the form, and means for positioning the member in contacting relation to the form.

78. A tire making machine including a support, a carriage thereon, a tire-form juxtaposed to the support, power-operated means for advancing the carriage toward the form, means for arresting such advancing movement of the carriage, power-operated means for returning it to normal position, a pressing-member on the carriage normally out of contact with the form, and independent means for pressing the member into contact with the form and for changing such contacting relation.

79. A tire making machine including a support, a carriage thereon, a tire-form juxtaposed to the support, power-operated means for advancing the carriage toward the form, means for arresting such advancing movement of the carriage, power-operated means for returning it to normal position, a pressing-member on the carriage normally out of contact with the form, means for pressing the member toward the form, and means for bodily shifting the member while being pressed toward the form.

80. A tire making machine including a support, a tire-form juxtaposed thereto, a carriage movable in relation to the form, fabric-manipulating means on the carriage, automatic means for effecting an advancing movement of the carriage toward the form, and means for automatically effecting a receding movement of the carriage away from the form.

81. A tire making machine including a support, a tire-form juxtaposed thereon, a carriage movable in relation to the form, automatic means for effecting an advancing movement of the carriage toward the form, automatic means for automatically effecting a receding movement of the carriage away from the form, and a fabric-manipulating device movable with the carriage and adapted to be also actuated independently thereof.

82. A tire making machine including a tire-form, mechanism for forming tire material on the form comprising a plurality of pressing-members adapted to have an advancing radial movement with respect to the form and engageable therewith, means for advancing said pressing-members toward the form and maintaining them thereagainst, power means for automatically effecting a receding movement of said members away from the form, and means for returning said members radially with respect to the form to normal position.

83. The combination of a support, a ro-

tatable form, a movable carriage shiftable in relation to the form, roller-sustaining means on the movable carriage, a fabric-roller carried by the sustaining means and bodily shiftable thereon, means operative to move the movable carriage relative to the form, means to move the sustaining means relative to the form during the movement of the movable carriage, and means for moving the roller relatively to said form during the movement of both the sustaining means and carriage, substantially as described.

84. The combination of a support, a rotatable tire-form, a carriage movable in relation to the form, a fabric-pressing member carried by and rotatable on vertical axis on the carriage, actuating mechanism for bodily shifting said vertical axis of the pressing-member on the carriage during the rotation of the form, actuating mechanism for moving said carriage in relation to the form during its rotative movement, and means for automatically arresting the actuation of said carriage-actuating mechanism when the carriage reaches a predetermined position.

85. The combination of a support, a rotatable tire-form, a carriage movable in relation to the form, a fabric-pressing member carried by and rotatable on a vertical axis on the carriage, actuating mechanism for bodily shifting said pressing-member on the carriage during the rotation of the form, actuating mechanism for moving said carriage in relation to the form during its rotative movement, means for automatically arresting the actuation of said carriage-actuating mechanism when the carriage reaches a predetermined position, and means for moving said pressing-member in relation to the form independently of but during the movement of the carriage.

86. The combination of a support, a rotatable tire-form, a movable carriage, a fabric pressing member carried by the carriage, a feed-screw operatively connected to said carriage and adapted to move the same, means for constantly rotating said screw, and means to automatically disconnect said carriage from said screw when said carriage reaches a predetermined position.

87. The combination of a support, a rotatable tire-form, a movable carriage, a fabric-pressing member carried by the carriage, a constantly rotatable screw, a nut carried by the carriage and adapted to be moved into and out of engagement with said screw, and means operative to move said nut.

88. The combination of a support, a rotatable tire-form, a movable carriage, a fabric-pressing member carried by the carriage, a constantly rotatable screw, a nut carried by the carriage and adapted to be moved into and out of engagement with said screw, and means for automatically moving said

nut out of engagement with said screw when said carriage reaches a predetermined position.

89. The combination of a support, a rotatable tire-form; a movable carriage, a fabric-pressing member carried by the carriage, a constantly rotatable screw, an engageable nut, an operating part carried by the carriage and connected to said nut and adapted when moved in one direction to move said nut into engagement with said screw and when moved in a reverse direction to move said nut out of engagement with said screw, and a stop arranged in the path of said operating part and adapted to engage and operate it to move the nut out of engagement with the screw when the carriage reaches a predetermined position.

90. A tire making machine including a supporting structure, a carriage mounted thereon, carriage-feeding mechanism including driving means, a constantly rotating feed-screw, means for connecting the carriage to the feed-screw at the will of the operator, and an adjustable carriage-stop arranged in the path of travel of the carriage and adapted automatically to arrest travel of the carriage at any of a plurality of points.

91. A tire making machine including a rotary tire form, a supporting structure, a carriage mounted thereon, fabric pressing means on the carriage, carriage-feeding mechanism including driving means, a constantly rotating feed-screw, means for connecting the carriage to the feed-screw at the will of the operator, and an adjustable carriage-stop arranged in the path of travel of the carriage and adapted automatically to disconnect the carriage from the feed-screw and thereby arrest travel of the carriage at any of a plurality of points.

92. In combination, a tire form, a carriage movable relatively thereto towards and from the same, a pair of stitchers operating on opposite sides of the form, and operating mechanism associated with each stitcher comprising an arm pivotally connected to the carriage, a second arm carrying a stitcher and pivotally supported upon the end of the first named arm, a spring associated with the second arm for yieldingly pressing the stitcher towards the form, a link connected to the rear end of said second arm, and means for shifting the link for changing the angular position of said second arm.

93. In combination, a tire form, a carriage movable relatively thereto towards and from the same, a pair of stitchers, a pair of arms carried by the carriage having their front ends movable simultaneously towards and from each other, a second arm associated with the forward end of each of the first named arms and carrying one of the stitchers, a link associated with the rear

end of each of said second arms with means for shifting the link for determining the angular position of the second arm, and a spring associated with the second arm for yieldingly pressing the stitcher carried thereby towards the form.

94. In combination, a rotary tire form, a support, one of said parts being movable towards and from the other, a pair of fabric pressing members on the support, said members being movably mounted to change their angular position relative to the fabric on the form, a treadle with connections for moving the fabric pressing members towards each other, and a hand controlled member with connections to the fabric pressing members for setting and holding them in the desired angular positions, substantially as described.

95. In combination, a tire form, a carriage with means for moving the same towards and from the form, fabric pressing members, one for each side of the tire form, supports for said fabric pressing members movably mounted to permit the fabric pressing members to assume different angular positions in respect to the tire form and a pair of pivotally mounted members with springs interposed between the same and the said supports for pressing the said supports with the fabric pressing members towards the sides of the form, substantially as described.

96. In combination, a tire form, a carriage movable towards and from the same, fabric pressing means thereon to apply fabric to the form, a machine driven screw shaft for moving the carriage, and a nut on the carriage shiftable into and out of engagement with the screw shaft, and means for shifting the nut and for returning the carriage to normal position, and manually controlled means for exerting pressure on the fabric presser means, substantially as described.

97. In combination, a tire form, a carriage movable towards and from the same, manually controlled fabric pressing means thereon to apply fabric to the form, a machine driven screw shaft for moving the carriage and a nut on the carriage shiftable into and out of engagement with the nut and means for automatically returning the carriage to normal position, substantially as described.

98. In combination, a tire form, a carriage movable towards and from the form, manually controlled fabric pressing means on the carriage to apply fabric to the form, a machine driven element for advancing the carriage, means engaging the carriage with and disengaging it from the machine driven element, and means for returning the carriage to normal position when disengaged and while said machine driven element con-

- tinues in movement, substantially as described.
99. In combination, a tire form, a carriage movable towards and from the same, fabric pressing members, arms on which said fabric pressing members are supported, said arms being movable towards and from each other, means for moving the arms relative to each other and to the fabric on the tire form as the carriage advances; said means including a spring at each arm whereby the fabric presser members individually are yieldingly held to their work, substantially as described.
100. In combination, a tire form, a reciprocable carriage, fabric pressing members, a part common to said members and means on the carriage operated by said part for correspondingly pressing the said members in unison against the fabric on the form, and springs, one for each fabric pressing member, forming a part of said means and permitting individual yielding action of said fabric pressing members.
101. In combination, a tire form, a reciprocal carriage, fabric pressing members, arms carrying said fabric pressing members and movable towards and from each other and the tire form, and manually operable means for exerting pressure on said arms at the will of the operator, and springs for transmitting said pressure, substantially as described.
102. In combination, a tire form, a carriage, fabric pressing members on opposite sides of the form, means for forcing them towards each other and the form and for retracting them laterally from the form and from each other, a power operated element for advancing the carriage, and means for disconnecting the carriage from the power operated element, and for returning the carriage to normal position, independent of said power operated element.
103. In combination, a tire form, a carriage, fabric pressing members on opposite sides of the form, means for forcing them towards each other and the form, and for retracting them from the form and from each other, a power operated element for advancing the carriage, means for automatically disconnecting the carriage from the power operated element, and for automatically returning the carriage to normal position, independent of said power operated element.
104. In combination in a tire making machine, a rotary tire form, fabric pressing members to act on opposite sides of the tire form, a support for the said members, said tire form and support having relative movement to make the fabric pressing members traverse the form substantially radially thereof, manually operated means for applying pressure to the fabric pressing members at the will of the operator to force them towards the central plane of the form during their traversing movement, and means for causing automatic retraction of the fabric pressing members laterally from the form and from each other when the said pressure is relieved, substantially as described.
105. In combination, a rotary core, a support for fabric pressing devices, means for moving one of said elements towards and from the other, a pair of arms pivotally carried by the support, means for swinging the arms towards each other, brackets connected to the arms by pivots about which the brackets are turnable, links connected with the brackets for turning them about their pivots, and means for operating the links, substantially as described.

In testimony whereof, I affix my signature in presence of two witnesses.

FERDINAND FRANCIS BRUCKER.
